UNITED STATES PATENT OFFICE

JOHN BECK, OF ASHLAND, WISCONSIN

REFRIGERATOR

Application filed March 2, 1928. Serial No. 258,494.

This invention relates to refrigerators in general and particularly, though not exclusively, to refrigerators which are of the type known as side icers.

It has been found that the air circulation within the refrigerator governs the amount of ice required to be used. If the air circulation within the refrigerating compartment is poor the ice will melt rapidly but the temperature within the refrigerator will be above that required to properly preserve the food and prevent it from spoiling. By providing a proper circulation of air the ice will melt at the proper rate to maintain desired low preserving temperature.

The present invention has for its object to provide improved means for circulating air about the ice so that the currents of air will come in contact with a relatively large surface area of ice.

Another object of the invention is to provide novel means for deflecting the currents of air so that a constant circulation of cold air is assured as long as there is any ice in the ice chamber.

And another object is to provide a new and novel arrangement of the drip pan and ice rack to obtain a constant circulation of air about the ice and in the refrigerator.

The accompanying drawings illustrate a selected embodiment of the invention and the views therein are as follows:

Fig. 1 is a sectional elevation of a refrigerator embodying my invention.

Fig. 2 is a detail plan section on the line 2—2 of Fig. 1.

Referring to the drawings, 1 designates a refrigerator of any suitable size, shape and construction and having insulated side walls 2, 2, a top 3, a bottom 4, a front 5 and a back 6. A division wall 7 is arranged substantially intermediate the sidewalls and provides an ice chamber 8 and a food chamber 9. Shelves 10 are arranged in a portion of the food chamber as shown.

A rack 11, preferably of open or lattice construction, is suitably arranged at the bottom of the ice chamber 8 to support a cake of ice 12. An insulated drip pan 13 is fixed to the division wall 7 and it inclines down-

wardly beneath the rack and towards the side wall to carry the drip from the ice to the drain 14 which leads to a suitable receptacle or pipe line (not shown). This pan is connected air-tight to the division wall 7 and to the back 6 of the refrigerator to prevent the passage of air at the joints where it is connected to these parts.

A skeleton frame 15 made of slats or other suitable means is spaced from the wall 2, and a similar frame 16 spaced from the division wall 7 to space the ice from these walls and also to provide cooling passages 17 and 18. The frame 16 is spaced relatively far from the division wall 7 and the passage 18 is substantially twice as wide as the passage 17. A projecting ledge or baffle 19, having a curved underside 20, deflects the air from the passages 17 and 18 to the common passage 21. This ledge or baffle is substantially triangular in cross-section, having a downwardly and inwardly inclined top connecting with the upper end of the curved side 20 at a point above the lower end of the drip pan 13. An inclined top member, or plate, 22 is arranged above the food and ice chambers to direct the air currents from the food chamber over the division wall 7 to the ice chamber above the ice therein.

Since the passage 18 is substantially twice as large as the passage 17, approximately sixty percent of the circulating air will pass therethrough and be cooled. The current of air discharging at the bottom of passage 18 will be deflected by the inclined pan 13 and pass under the ice and be further cooled thereby. Approximately 60 per cent of the air transmitted passes under the ice and comes in direct contact with the underside of it, thereby carrying and distributing the cold units equally throughout the cooling chamber. The drip from the rack also has a cooling effect on the air and also cleanses it by absorbing and carrying away odors and gases therefrom.

The remainder of the circulating air will pass through the passage 17 and be cooled therein. The ledge 19 deflects the air from both passages 17, 18 through the common passage 21 into the food chamber. By pro-

viding an inclined top member 22 I maintain a constant circulation of air within the refrigerator and eliminate stagnant warm air pockets.

5 I have provided a refrigerator in which a constant circulation of clean cold air is maintained, and which maintains a lower temperature and uses less ice for cooling purposes than the conventional type of refrigerator.

10 I am aware that changes in the form, construction and arrangement of the parts may be made without departing from the scope, or sacrificing any of the advantages of the invention and I reserve the right to make all such changes as fairly fall within the scope of the following claims.

I claim:

20 1. A refrigerator comprising a top and bottom, front and back, and two sides, a division wall intermediate said sides, skeleton frames spaced from said division wall and from one of said sides and forming air passages, a rack below said frames for supporting a cake of ice, an inclined drip pan fixed to said division wall and to said back and having an air-tight connection therewith, and spaced from a side to form a passage communicating with the space below said drip pan, an inclined member arranged beneath said top, and a baffle fixed to one of said side walls between the rack and the normal plane of the drip pan.

25 2. A refrigerator comprising a top and bottom, front and back, and two sides, a division wall, a skeleton frame spaced from one of said side walls to form an air passage, a skeleton frame spaced from the division wall to form an air passage substantially twice 40 as wide as said first passage, a rack between said frames for supporting a cake of ice, an inclined insulated drip pan arranged between said rack and connected air-tight to the bottom of said division wall and to said back and spaced from one of said side walls to form an air passage communicating directly with the space below the drip pan, a baffle arranged above said last named passage and below the rack and deflecting air 45 from both of said first named passages and through said last named communicating passage, and an inclined member beneath said top for deflecting air to both of said first named passages.

50 3. In a refrigerator, means for supporting a cake of ice, means for deflecting a current of air in said refrigerator along and in direct contact with one side and the bottom of the ice, means for deflecting a current of air in 55 direct contact with and over the top of the ice and along the other side thereof, and means for deflecting the air from both of said sources through a common passage.

4. In a refrigerator having oppositely disposed walls and a back forming an ice com-

partment, an insulated drip pan connected air tight to one of said walls and to said back and inclined downwardly toward the other wall, the lower side of said pan being spaced from said other wall to form an air passage, 70 and a curved baffle on said other wall and spaced from the lower side of the pan to deflect the air downwardly through said passage.

5. In a refrigerator comprising a food 75 chamber and an ice chamber with a division wall therebetween spaced from the top of said refrigerator to provide intercommunication between said food and ice compartments, said division wall also being spaced 80 from the bottom of said refrigerator, means providing vertically extending flues disposed on opposite sides of said ice chamber, one of said flues being disposed along said division wall and the other of said flues being 85 disposed along the wall of said refrigerator opposite thereto, means for supporting ice in said ice compartment between said flues, and an insulating deflecting member extending from the lower end of said division wall below said supporting member, another deflecting member disposed below the flue on said side wall of said refrigerator, said flues being arranged in spaced apart relation to provide an opening whereby air passing through 90 said flues and into engagement with said deflectors will be directed by said deflectors across and below said supporting means toward said opening to pass therethrough into 95 said food compartment.
